UNITED STATES PATENT OFFICE.

HENRY S. WELLES, OF NEW YORK, N. Y.

ARTIFICIAL BAIT.

1,101,223.

Specification of Letters Patent. Patented June 23, 1914.

Application filed July 24, 1912. Serial No. 711,241.

To all whom it may concern:

Be it known that I, HENRY S. WELLES, a citizen of the United States, residing in the city of New York, borough of Manhattan, in the county and State of New York, have invented a certain new and useful Improvement in Artificial Baits, of which the following is a specification.

The invention relates to floating baits for trolling and casting, and the object of the invention is to provide a bait of this class which shall float when resting idly in the water and be automatically submerged a short distance beneath the surface of the water by the action of the latter thereon due to the movement of the boat in trolling or the recovery of the line in casting.

The invention consists in certain novel features and details of construction and arrangement by which the above object is attained, to be hereinafter described.

The accompanying drawings form a part of this specification and show several forms of the invention as it has been carried out in practice.

Figure 1 is a side view showing a preferred form of the invention as it appears in action in the water. The remaining figures are on a larger scale. Fig. 2 is a side view of the bait shown in Fig. 1. Fig. 3 is a corresponding plan view. Fig. 4 is a front view of the same, and Fig. 5 is a rear elevation. Fig. 6 is a side view of a modified form of the bait, and Fig. 7 is a corresponding plan. Fig. 8 is a side view of another modification and Fig. 9 is a top or plan view of the same. Fig. 10 is a side view showing the improved bait in its simplest form, and Fig. 11 is a corresponding plan view. Fig. 12 is a side elevation of another modification.

Similar letters of reference indicate like parts in all the figures.

The invention is based on a popular type of floating bait termed a "plug" consisting essentially of a short cylindrical length of wood equipped with hooks and adapted to be drawn through the water. Many variations of this type are used and in all the forms the bait is drawn along the surface of the water. In the present improvement the plug is constructed with an inclined face presented to the action of the water, and so arranged as to cause the plug to descend when in action and travel a short distance beneath the surface in following the line.

Referring to Figs. 1 to 5 inclusive, A is

the body of the plug which may be of light wood, preferably semicylindrical in general cross-section, with the flat face beneath and having its front face B practically plane and inclined forwardly and downwardly toward the extreme front edge or nose, and having at the rear an enlargement or boss C with its front face D also inclined parallel with the face B, as shown. The rear of the boss is shown as perpendicular to the under face of the plug.

At a high point on the face or plane B is an eye E or other convenient means for attaching a line E¹ by which the plug is drawn through water, and on the under face are hooks F which may be single hooks hung as low as practicable or gangs as shown, serving by their weight as ballast for the plug and insuring its proper presentation to the water. Additional or other ballasting means may be employed especially when the size and number of hooks is reduced, to insure the immediate assumption of position on striking the water in casting.

The upper portion of the boss C is shown as notched or grooved longitudinally of the body A to provide a channel as at G, serving to induce a tendency of the plug to travel a straight path in following the line.

The inclined face or forward plane B induces the tendency to dive, while the rear plane D tends to hold the rear end down and cause the plug to lie approximately parallel with the surface of the water. Experiment has shown that the maintenance of this position is aided by the hollowed or curved throat H in the under face of the plug near the front and the slightly curved forward edge or nose J of the plane B, and that a plug thus constructed will travel in a position parallel with the water surface and a few inches beneath such surface, the depth depending upon the speed at which the bait is drawn through the water and the amount and location of the ballast.

Many successful trials have demonstrated that the improved plug is an extremely efficient bait for game fish, both in casting and trolling.

Figs. 6 and 7 show a form in which the forward and rear planes B¹ and D¹ on the body A¹ are supplemented by an intermediate inclined diving face K parallel with the others, and otherwise modified as to form, as shown.

Figs. 8 and 9 show a modification in which

the planes B² and D² are similar to the corresponding surfaces in Figs. 2 and 3 but with the body A² rounded on the under face.

5 Figs. 10 and 11 show an extremely simple form in which the body A³ is a simple cylinder cut off at an inclination at one end to produce the plane B³.

In Fig. 12 the body A⁴ is of spindle form and equipped with a plurality of disks B⁴, 10 D⁴ and K¹ serving as planes.

The general action is the same in all the forms.

Other modifications may be made in the 15 forms and proportions and in the number and arrangement of the hooks or other ballasting means, and in the location of the eye for the attachment of the line or leader.

I claim:—

20 1. An artificial bait comprising a body of one integral piece of less gravity than water provided with means for the attachment of a line, hooks on the lower portion of said body, said body having its front end upon its upper face beveled to form a forwardly and downwardly inclined plane surface to induce submersion when said body is drawn through the water, said body having a hollow throat adjacent to and in rear of said inclined face.

25 2. The artificial bait described, comprising a body of one integral piece of less gravity than water, said body having its forward end upon its upper face beveled to form a downwardly and forwardly inclined plane surface and its rear end having an inclined face, said body having a hollow throat on its under surface to the rear of said inclined front face.

30 3. The artificial bait described comprising

a body of one integral piece of less gravity 40 than water, hooks on the lower portion of said body, said body having its front end beveled to form a forwardly and downwardly inclined plane surface and having a longitudinally arranged groove in its upper face, a boss at the rear end of said body, said boss having its front face inclined forwardly and downwardly, and an eye on the upper portion of said front end.

4. The artificial bait described comprising 50 a body of one integral piece of less gravity than water, hooks on the lower portion of said body, said body having its front end beveled to form a forwardly and downwardly inclined plane surface and having a 55 longitudinally arranged groove in its upper face, a boss at the rear end of said body, said boss having its front face inclined forwardly and downwardly, and an eye on the upper portion of said front end, said body 60 having a hollow throat on its under face beneath such inclined front end.

5. A bait comprising a body having forwardly-downwardly extending means carried thereby adapted to lower the body as 65 the same is drawn through the water, hooks secured to the bottom of the body, and means attached to said forwardly-downwardly extending means for securing a draft line to the bait.

In testimony that I claim the invention above set forth I affix my signature, in presence of two witnesses.

HENRY S. WELLES.
